UNITED STATES PATENT OFFICE.

FRANK W. SIMMONS, OF ATLANTIC CITY, NEW JERSEY.

CONNECTING-BAR OR HANGER.

1,057,890.

Specification of Letters Patent.

Patented Apr. 1, 1913.

Application filed October 1, 1912. Serial No. 722,422.

To all whom it may concern:

Be it known that I, FRANK W. SIMMONS, a citizen of the United States, residing at Atlantic City, in the county of Atlantic and State of New Jersey, have invented certain new and useful Improvements in Connecting-Bars or Hangers; and I do hereby declare the following to be a full, clear, and exact description of the invention, such as will enable others skilled in the art to which it appertains to make and use the same.

This invention relates generally to devices for connecting the inlet and outlet pipes of a gas-meter or other device through which a fluid is designed to pass, but more particularly to a support or hanger for gas-meters; and it consists of a bar having communicating inlet and outlet passages at one end and inlet and outlet passages at the opposite end, through which fluid is designed to pass.

The invention also consists of means for adjusting the hanger or connecting-bar to any desired length to render it applicable to different widths of devices through which the fluid is to pass. And the invention further consists of the general construction, arrangement and combination of the several parts, as will be hereinafter fully described in this specification and briefly stated in the claims.

One of the chief objects of the invention is to so construct the connecting-bar or hanger, that the fluid will be taken in from a service-pipe at one end, and passed out through the other end to a distributing-pipe, after passing through the device to which it is connected.

Another object of the invention is to so construct the bar or hanger that it may be attached to or suspended from a distributing-pipe and have a passage in communication with said pipe, and a passage in communication with a distributing pipe.

45 These and other objects are accomplished by means of the mechanism illustrated in the drawing, in which—

Figure 1 is a front elevation of my improved bar or hanger, showing, as an example, a gas-meter supported thereby; Fig. 2 is a vertical, longitudinal section of the bar or hanger, and Fig. 3 a horizontal, longitudinal section of the same.

Referring to the several views, the numeral 55 1 indicates the bar or hanger which is provided at one end with an inlet passage 2,

the wall of which is internally screw-threaded to receive the screw-threaded end of the usual service-pipe, not shown. The passage 2 is intersected by an outlet-passage 3, the wall of which is internally screw-threaded for the reception of a screw-threaded coupling-nut 4 for connecting the inlet-pipe 5 of the meter 6 with said passage 3. The other end of the hanger is provided with a passage 7 intersected by an outlet-passage 8, formed in an extension 9. The upper end of the extension is externally screw-threaded to receive a screw-threaded union-coupling 10 which connects the hanger with an internally screw-threaded house-line connection 11, in which the distributing or house-line pipe, not shown, is screwed.

Screwed into the passage 7 is an adjustable pipe extension 12 of elbow shape, through which the fluid passes from the meter, said pipe having its outer end internally screw-threaded to receive the coupling-nut 13 which connects said pipe extension with the outlet-pipe 14 of the meter, a jam-nut 15 being employed to hold the pipe extension in adjusted position. One of the important features of the invention is the adjustability of the bar or hanger to adapt it to any width of meter, allowing for the easy and ready removal of one width meter and its replacement with another of less or greater width.

It will be noted that the meter will be supported at opposite sides, and that the hanger will be supported at two separate points, at one end by the service-pipe, to which it is to be connected, and approximately centrally by the house-distributing pipe.

My improved bar or hanger is readily and quickly connected to the house-distributing pipe; is neat and attractive in appearance; forms a strong and durable support for the meter or connection for other fluid devices, and is simple and inexpensive in construction.

Having thus fully described my invention, what I claim is:

1. A support for meters, comprising a casting provided at one end with a screw-threaded inlet to adapt it to be screwed to a service-pipe, and with a screw-threaded outlet for direct connection with the meter inlet-pipe, said outlet being in communication with said inlet, and at the other end with a screw-threaded opening and an outlet-

passage in communication with each other, and an outlet-pipe adjustable in said screw-threaded opening so as to lengthen or shorten the support to accommodate different widths of meters, and having its outer end screw-threaded for direct attachment to the meter outlet-pipe.

2. A meter support, comprising a bar having at one end an inlet and an intersecting outlet for direct connection with the meter inlet-pipe, and at the other end a screw-threaded opening and an intersecting outlet passage, an elbow-shape pipe having one end screw-threaded to adapt it to be 15 screwed into said screw-threaded opening and its other end screw-threaded for direct attachment to the meter outlet-pipe, said elbow-shape pipe being adjustable so as to lengthen or shorten the bar to accommodate 20 different widths of meters, and means for holding the elbow-shape pipe in adjusted position.

3. A meter-support comprising a casting provided at one end with a screw-threaded inlet to adapt it to be screwed to a service-
21 pipe, and with a screw-threaded outlet for direct communication with the meter inlet-pipe, said inlet communicating with said outlet, and at the other end with a screw-threaded opening and an intersecting outlet 25 passage situated between the respective ends of the casting, and an outlet pipe lengthwise adjustable in said screw-threaded opening, whereby the support may be lengthened or shortened said outlet-pipe having its outer 30 end screw-threaded for direct attachment to the meter outlet-pipe.

In testimony whereof I affix my signature, in the presence of two witnesses.

FRANK W. SIMMONS.
